UNITED STATES PATENT OFFICE.

MARY IRENE SNAPE, OF SPRINGFIELD, ILLINOIS.

ENVELOPE AND ENVELOPE BLANK.

Application filed May 4, 1926. Serial No. 106,665.

This invention has reference to two compartment envelopes which furnish an integral package for mailing articles subject to different postal rates and which ordinarily 5 are sent separately.

My invention has for its principal object a two compartment envelope which is especially adapted for mailing automobile license plates and the certificate of registration. The license plates are placed in the larger compartment which is accessibly closed at the factory. When the license is assigned, certificate of registration is issued to the applicant and the certificate is placed 10 in the smaller compartment, which latter is provided with a window, and serves as an address label for the package. The larger compartment is completely and securely formed as also is the smaller compartment; 15 each being complete in itself but only a part of the whole, thus strengthening the package and insuring the delivery of the same to the addressee with the contents intact.

20 An additional object is to provide a two compartment envelope of such simple construction that it requires but slightly more material and skill to manufacture, than in the instance of an ordinary envelope but 25 with the added virtue of transmitting two different classes of mail in the one package.

A further object is to so position the smaller compartment on the face of the envelope that the flap for inaccessibly closing the 30 smaller compartment can be moistened without dampening the front of the envelope and can also be sealed rapidly and securely.

The invention contemplates a two compartment envelope for the purposes herein 35 stated, and for all and such other purposes in which it may be desirable to mail things subject to different postal rates.

That the invention may be more fully understood, reference is had to the accompanying drawings forming a part of the present description, illustrating a preferred embodiment of the invention, in which:—

Figure 1 is a view of the blank when out, 40 from which the envelope embodying my invention is formed;

Figure 2 is a front view of the completed envelope embodying my invention, made 45 from the blank shown in Fig. 1, and

Figure 3 is a section on line 3—3 of Fig. 50 2, showing the parts as in use.

The blank is illustrated in Fig. 1 and

comprises a front 1 having end flaps 8 and 9 each of which latter is gummed as indicated at 22 and 23 respectively, and which fold on lines *e* and *f* respectively. A back 60 2 is disposed on one side of front 1, while an extension 3 is disposed on the opposite side of the front, the back and the extension being foldable along lines *a* and *b*, which latter may be scored if desired. The back 65 24 and the extension 3 have gummed parts 24 and 20 along their outer longitudinal edges *c* and *d*. A flap 4 extends outwardly from the outer longitudinal edge of back 2 and is gummed as indicated at 25.

70 The front 1 is formed with a window 6 and with an entrance slot 7, while the extension 3 is provided with transverse gummed lines 21.

In forming the envelope, extension 3 is 75 folded to underlie front 1 and is pasted thereto, whereby a small pocket 5 is formed for the registration card C or other article, which pocket has an area defined by the lines *g*, *h* and *i*, in Fig. 1. The back 2 is 80 next pasted down onto the extension 3 and finally the flap 9 is pasted down onto the back. The parts now appear as in Figure 85 2 and upon insertion of the card or other matter C through slot 7 into compartment 5, flap 4 is then pasted down over the front 1 to close the slot 7 as shown in Fig. 3, and upon insertion of the license plate or other article P into the large pocket or compartment 10, the flap 8 is pasted down in position and 90 the envelope is ready for mailing. The window 6 in the front wall 1 may be and preferably is covered with a transparent sheet which is pasted along its longitudinal edges and inner transverse edges to front 95 wall 1 but in order to lessen manufacturing cost, this transparent sheet may be omitted.

95 While the foregoing described envelope is especially adapted for mailing automobile license plates and the accompanying registration card, it is of course understood there is no limit to the use to which the same may be put, and whatever, the character or description of the article mailed in the larger compartment, the smaller compartment or pocket may contain the name and address of the addressee which may appear on a letter, small envelope containing a letter or other piece of first class mailable matter.

105 If the window 6 is omitted, the address can be placed on the envelope, preferably in the area described by the lines *g*, *h* and *i*.

The return address of the sender may appear at the upper left hand corner of the envelope, in the usual manner.

While the foregoing described two compartment envelope has its value as a container for automobile license plates and the accompanying registration card, it is of course understood there is no limit to the uses to which the same may be put, and whatever the character or description of the matter or article mailed in the larger compartment, the smaller compartment or pocket may contain the name and address of the addressee on any piece of first class mailable matter.

I contemplate the usual modifications in the details of my invention as may occur in its commercial development, and without departure from the spirit of the appended claims.

What is claimed is:—

1. In an envelope, a sheet having longitudinal score lines thereon to provide front, back and intermediate portions, said front and back portions being of substantially the same width, end flaps carried by said front portion, said front portion having a sight opening and a slit parallel with and adjacent to said opening, said intermediate portion having its free side edge gummed and having a pair of spaced transverse gummed lines extending from its inner edge at right angles to said slit and intersecting the gummed portion of the free side edge to form a pocket about the slit and opening when the said intermediate portion is moved into engagement with the front portion, and a flap carried by the free edge of the back portion intermediate its ends to provide a fastener to secure the back portion to the

front portion and to further provide a cover for the slit and a reinforcement for the upper edge of said pocket whereby to form a two compartment envelope for mailing objects having different rates of postage.

2. In an envelope, a sheet having a pair of longitudinal score lines thereon to provide front, back and intermediate portions, said front and back portions being of substantially the same width, end flaps carried by said front portion, said front portion having a sight opening and a slit parallel with and adjacent to said opening, said intermediate portion being of less width than the front and back portions and having its free side edge gummed and further having a pair of spaced transverse gummed lines extending from its inner edge at right angles to said slit and intersecting the gummed portion of the free side edge to form a pocket about the slit and opening when the said intermediate portion is moved into engagement with the front portion, said back portion having its free side edge gummed to provide a fastener for the same and to form a second compartment when the back is moved into engagement with the intermediate portion, and a flap secured to the free edge of the back portion to provide a cover for the slit, said flap being formed so that when folded over the fold line between the front and intermediate portions same contacts with said fold line between the front and intermediate portions to provide a reinforcement for the upper edge of the first named compartment.

In witness whereof, I have hereunto affixed my hand this 22nd day of April, 1926.

MARY IRENE SNAPE.
